UNITED STATES PATENT OFFICE.

GLENN H. CURTISS, OF BUFFALO, NEW YORK, ASSIGNOR TO CURTISS AEROPLANE AND MOTOR CORPORATION, A CORPORATION OF NEW YORK.

DRAFT SYSTEM FOR FLYING-BOATS.

1,246,018.

Specification of Letters Patent. Patented Nov. 6, 1917.

Application filed November 18, 1916. Serial No. 132,106.

To all whom it may concern:

Be it known that I, GLENN H. CURTISS, a citizen of the United States, residing at Buffalo, in the county of Erie and State of New York, have invented certain new and useful Improvements in Draft Systems for Flying-Boats, of which the following is a specification.

This invention relates to heavier-than-air flying machines and more particularly relates to an improved draft system for multimotored hydroaeroplanes and flying boats.

In the larger high powered types of aircraft, where the thrust value is enormous, it is customary to locate the several motor units of a multiple unit power plant intermediate the supporting surfaces or planes, each motor unit having an individual mounting which, in a "Curtiss" type of flying boat, may be generally described as comprising front and rear wing post frames and engine bed beams intermediately interconnecting them. By this arrangement the center of thrust is removed from the plane of the center of resistance for location considerably above the hull or body of the craft. Bearing in mind the relation and location of these two theoretical centers and the enormity of thrust value occasioned by the simultaneous operation of the several power units, it is evident that some means must be provided whereby the full thrust stresses may be directly and effectually transmitted laterally inwardly to regions of resistance or drift. Hence, it is to this end that the present invention is designed.

Another and important object of the invention resides in the utilization of built-in wing spars in connection with the cross-arranged lift and drift wires for transmitting the thrust stresses interiorly of the hull.

In describing my invention in detail, reference will be had to the accompanying drawings wherein like characters of reference designate like or corresponding parts throughout the several views, of which:

Figure 1 is a front elevation of the engine section of a flying boat illustrating diagrammatically the arrangement of cables and struts utilized in the transmission of thrust stresses directed to the interior of the hull;

Fig. 2 similarly illustrates the arrangement referred to in side elevation;

Fig. 3 is a perspective view illustrating by

shaded lines the relative arrangement of the draft system units, and

Fig. 4 is a detail perspective view.

Before undertaking a general description of the system of my invention, it is to be thoroughly appreciated that it is not my intention to limit the application of the invention to multimotored flying boats although craft of this type had been and are being developed (almost exclusively) along larger lines.

The hull or body of the craft, indicated by dotted lines in Figs. 1 and 2 and designated in its entirety by the numeral 10, may be generally described as comprising a fore body 11, an extended tail 12, and fin ex- 70 crescentes 13, the latter augmenting laterally the hydroplaning bottom and extending rearwardly from the bow aft to a planing step 14 located in the approximate transverse vertical plane of the center of gravity 75 designated CG.

Built-in wing spars 15 and 16 extend intermediately across the hull, one in advance of and the other aft of the vertical plane of the step 14. These spars collectively constitute 80 a base for the engine section panel of the lower supporting plane 17.

Front and rear wing post frames designated respectively 18 and 19 interconnect the engine section panel of the lower supporting 85 plane 17 with the engine section panel (not shown) of the upper supporting plane. Wing spars 20 and 21, equal in length to the wing spars 15 and 16, constitute a base for the upper engine section panel to accordingly 90 provide with the lower panel, an engine section biplane cell which in length is sufficient to extend laterally considerably beyond the sides of the hull.

Center struts, front and rear, designated 95 22 and 23 interconnect and brace the wing spars of the engine section panels. These struts, together with struts 24 and 25 which extend inwardly diagonally from the front and rear wing post frames downwardly 100 in converging relation to the spars 15 and 16 respectively at the foot of each center strut 22 and 23, effectually brace the biplane panel cell.

Engine bed beams 26, arranged in pairs, 105 interconnect the longitudinally aligned wing post frames 18 and 19 to support the power units, of which in the present instance there

are two arranged intermediate the supporting surfaces of the machine. The downwardly converging braces 24 and 25 engage at the terminals of the engine beds to transmit all lateral stresses to the beams 15 and 16 at the foot of the center struts 22 and 23. Lift and drift wires 27, cross arranged, tie up the cell to constitute it a rigid unified whole. The motor units I have designated 10 28 and 29.

The foregoing construction and arrangement of parts, although admittedly preferred, forms no part of the invention disclosed except insofar as it functions in combination with the draft system hereinafter disclosed. Having in mind the relation and location of the theoretical center of thrust and the theoretical center of resistance designated on the drawing as C. T. and C. 15 R., respectively (referred to hereinbefore), together with the enormity of thrust value occasioned by the simultaneous operation of the two power units, it is evident that a means must be provided to transmit the total thrust stress from the power units to the interior of the hull. With this in view, cables 30, two in number, interconnect the opposed motor beds at their forward ends with the rear center strut 23 in a horizontal 20 plane and at a point directly in line with the rear upper terminal of a forwardly and downwardly extending diagonal brace 31. This brace 31 lies in the vertical plane of the fore and aft axis of the machine to engage at its lower forward end with the wing spar 15 at the foot of the center strut 22 and in alinement with an interior brace 32 arranged to abut respectively the said spar 15 and a compression block 33 located interiorly 25 of the hull at the center thereof for contact with the interior surface of the hydroplaning bottom. The brace 31 may be described as an exterior continuation of the brace 32. By the arrangement described, 30 the total thrust value is directly transmitted to a point of maximum resistance, namely, the hydroplaning bottom of the hull. In flight and in landing, the cables 30 are under tension; the braces 31 and 32 under compression; and the total number of exposed braces minimized.

Certain of the cross-arranged lift and drift wires 27 in connection with the stub wing structures supplement the stress transmission laterally inwardly from the motor units to the compression brace 32.

To compensate for drift strains incident to flight, cables 34 extend from the rear upper wing spar 21 at points of intersection 35 with the wing post frames 19 forwardly and downwardly to the engine beds 26 to points where the cables 30 are fastened and the lateral braces 24 engage. Drift strains are in this way also transmitted, via the cables 30 and the compression member 31-32, di-

rectly to the hydroplaning bottom of the hull.

For obvious reasons it is impractical in a multi-motored machine to provide a plural number of compression members, one for each motor unit. To do so would add 70 enormously to the head resistance without a proportionate gain in strength. By the draft system which I have evolved, the total thrust and landing stresses are directly carried to the interior of the hull and there uniformly distributed by the utilization of a single compression member, 31-32 in conjunction with cables 30 which directly connect the outer rear end of the compression 75 member to the forward end of the engine beds or spars.

Although I have described more or less precise forms and details of construction, I do not intend to be understood as limiting 80 myself thereto as I contemplate changes in form, the proportion of parts and the substitution of equivalents as circumstances may suggest or render expedient and without departing from the spirit of the invention 85 as claimed.

What is claimed is:

1. In an aircraft, the combination with supporting surfaces, a body, and a multiple unit power plant, of a compression 90 member arranged to transmit thrust stress forwardly into said body, and a draft system arranged intermediate the motor units for connection with said member.

2. In an aircraft, the combination with supporting surfaces, a body, and a multiple unit power plant, of a diagonally downwardly and forwardly inclined compression member arranged to transmit thrust stress forwardly into said body, and a draft system 100 arranged in a horizontal plane intermediate the motor units for connection with said member.

3. In an aircraft, the combination with supporting surfaces, a body, and a multiple 110 unit power plant, of a compression member extended at one end into the interior of said body, and a draft system including tension cables arranged for connection respectively with the several motor units and said member.

4. In an aircraft, the combination with supporting surfaces, a body, and a multiple unit power plant including motor units arranged symmetrically at opposite sides of 120 the longitudinal axis of the craft, of a draft system comprising tension cables arranged for connection at one end to the respective motor units and for intersection at their opposite ends at a point in the vertical plane 125 of said axis, and a compression member arranged for contact at said point of intersection to transmit thrust stresses forwardly into said body.

5. In an aircraft, the combination with 130

- supporting surfaces, a body, and a multiple unit power plant, of a compression member arranged to extend into said body from without at a point intermediate the leading 5 and trailing edges of said supporting surfaces, and a draft system including cables commonly connected to said member at the point aforementioned and separately connected to the several motor units.
- 10 6. In an aircraft, the combination with supporting surfaces, a body, and a multiple unit power plant, of a compression member arranged to extend diagonally downwardly and forwardly from a point without and in- 15 termediate the supporting surfaces to a point within said body, and a draft system including tension cables arranged to extend forwardly from a common point of connection with said compression member to the 20 separate motor units.
7. In an aircraft, the combination with supporting surfaces, a body, and a multiple unit power plant arranged to locate the center of thrust in a plane out of alinement 25 with the plane of the center of resistance, of a compression member arranged to extend from a point in the horizontal plane of the theoretical center thrust forwardly into said body, and a draft system arranged to inter- 30 connect said member and the several motor units.
8. In an aircraft, the combination with supporting surfaces, a body, and a multiple unit power plant arranged to locate the center of thrust in a plane out of alinement 35 with the plane of the center of resistance, of a compression member arranged to extend diagonally downwardly and forwardly from a point in the horizontal plane of the theo- 40 retical center of thrust into said body, and a draft system including cables commonly connected to said member and separately connected to the several motor units.
9. In an aircraft, the combination with 45 supporting surfaces, a body, and a multiple unit power plant arranged to locate the center of thrust in a plane out of alinement with the plane of the center of resistance, of a compression member arranged to extend 50 into the interior of the hull from a point without and intermediate the supporting surfaces, and a draft system arranged in the horizontal plane of said center of thrust to interconnect the compression member and 55 several motor units.
10. In an aircraft, the combination with supporting surfaces, a body, and a multiple unit power plant arranged to locate the center of thrust in a plane out of alinement 60 with the plane of the center of resistance, of a compression member arranged to extend from a point in the horizontal plane of the
- theoretical center of thrust forwardly to a point of maximum resistance interiorly of said body, and a draft system including ten- 65 sion cables commonly connected to said mem- ber at its aft extended terminal and sepa- 70 rately connecting the several motor units forwardly of its point of connection with said member.
11. In an aircraft, the combination with supporting surfaces, a body, and a multiple unit power plant arranged to locate the center of thrust in a plane out of alinement with the plane of the center of resistance, of a compression member arranged to extend forwardly into the interior of said body from a point in the horizontal plane of said center of thrust, tension means connecting the extended aft terminal of said compres- 80 sion member with the separate motor units, a tension means for transmitting the drift stresses directed to the interior of said body via the tension means and compression mem- 85 ber aforesaid.
12. In an aircraft, the combination with supporting surfaces, a body, and a multiple unit power plant arranged to locate the center of thrust in a plane out of alinement 90 with the plane of the center of resistance, a tension means for transmitting the drift stresses to the motor unit supports direct, a compression member arranged to extend into the interior of said body for contact at a point of maximum resistance, and tension 95 means for transmitting said stresses com- monly to said compression member from the respective motor unit supports.
13. In an aircraft, the combination with supporting surfaces, a body, and a multiple 100 unit power plant, of a draft system includ- ing tension devices arranged for rearward extension from the respective motor units and a thrust transmitting means arranged to continue the transmission of thrust 105 stresses into the interior of said body.
14. In an aircraft, the combination with supporting surfaces, a body, and a multiple unit power plant, of a draft system includ- 110 ing tension cables arranged to extend rear- wardly from the respective motor units, and a means for continuing the transmission of thrust stresses into the interior of said body via the supporting surfaces.
15. In an aircraft, the combination with supporting surfaces, a body, and a multiple unit power plant, of a draft system includ- 115 ing a compression member arranged to ex- tend interiorly of said body, and a means arranged to transmit thrust stresses by in- 120 dependent paths commonly to said member.

In testimony whereof I affix my signature.

GLENN H. CURTISS.
